UNITED STATES PATENT OFFICE.

JACOB HOHL, OF WEEHAWKEN, AND ERNEST G. KELLER, OF NEW DURHAM, NEW JERSEY.

EMBROIDERY MACHINE.

Application filed November 10, 1923. Serial No. 674,050.

To all whom it may concern:

Be it known that we, JACOB HOHL and ERNEST G. KELLER, both citizens of the United States, and residents, respectively, of Weehawken, Hudson County, State of New Jersey, and New Durham, Hudson County, State of New Jersey, have invented certain new and useful Improvements in Embroidery Machines, of which the following is a specification.

This invention relates to improvements in embroidery machines, and particularly to embroidery machines of the Schiffli type, in which the embroidered fabric is disposed vertically and the needles are reciprocated horizontally.

An object of this invention is to produce a machine of the type specified in which a single movement of a guiding element for ornamental material, such as threaded beads, cord, braid, chenille or the like to be sewed on to the fabric, will be effective to enable such ornamental material to be accurately guided to faithfully follow any design throughout any angle or angles thereof, thus avoiding complicated plural or compound movements and also avoiding the necessity of stopping the machine to change the movement in order to follow the design.

Another object of this invention is to provide a machine of the said Schiffli type with means whereby such ornamental material may be sewed to the fabric by the thread carried by the needles of the machine with straight stitches formed in the line of the design, as distinguished from zig-zag stitches across the line of the design, thus closely simulating hand work.

Another object of this invention is to provide a movement for the guide preferably comprising an oscillating movement which will enable the ornamental material to be swung at all times to similar angles at opposite sides of the line of the design, irrespective of the character of said design or the relative angles formed therein, thus enabling the use in such machine of straight line, as distinguished from zig-zag stitching at all points of the design, and furthermore to produce a movement which will also enable an effective angle to be procured by the movement of the guide.

Another object of this invention is to cause the guiding element to have a general design-following arcuate movement about the needle as an axis, by which the line of the design may be accurately followed, and furthermore to cause said guiding element to have an oscillating movement about the same axis for the purpose of oscillating the ornamental material to opposite sides of the line of the design at such angles as will enable ornamental material to be sewed to the fabric by a straight line of stitching in the line of the design.

Another object of this invention is to provide power-actuated means preferably comprising an electric motor for moving the guide in its arcuate design following path.

Another object of this invention is to provide means for indicating the position of the guiding element in relation to the needle whereby an operator may readily follow the design.

Another object of this invention is to provide a position-indicating pointer on the pantograph in combination with and movable in an arcuate or circular path about the needle or stitching pointer of said pantograph, so that the operator may at the same time readily make the stitching movement by the pantograph pointer and also by simple manipulation turn the guiding element to follow the design in advance of the needle or stitching pointer, and also preferably to provide power actuating means such as a switch or switches on such pantograph for rotating a motor in opposite directions to move the guiding elements along said design-following line.

Another object of this invention is to enable the design-following movement of the guiding element to be accomplished by simple rotary movement of a shaft and to accomplish the oscillating movement of such guide by an independent reciprocating movement of the same shaft.

With these and other objects in view, the invention comprises the combination of members and arrangement of parts so combined as to co-act and cooperate with each other in the performance of the functions and the accomplishment of the results herein contemplated, and comprises in one of its

adaptations the species or preferred form illustrated in the accompanying drawings, in which:—

Fig. 1 is a front elevation of a portion of a machine embodying this invention;

Fig. 2 is a section on the line 2—2 of Fig. 1;

Fig. 3 is a section on the line 3—3 of Fig. 1 looking in the direction of the arrow;

Fig. 4 is a section on the line 4—4 of Fig. 1, illustrating the spiral gears employed by us for transmitting motion to the guide operating shafts;

Fig. 5 is an enlarged view of the guide-operating wheel preferably employed by us.

Fig. 6 is a longitudinal section of the said guide-operating wheel and adjacent supporting means with the parts thereof disassembled from its frame;

Fig. 7 is a diagrammatic view of the reciprocating movement to opposite sides of the design following position of the guide.

Referring now to these drawings, which illustrate a preferred embodiment of our invention, 1 indicates a frame member of a Schiffli embroidery machine, 2 the spanner or fabric frame, 3 the design board, 4 a hand-operated pantograph for tracing the design on the design board, and 5 (Fig. 2) indicates the usual needle bar carrying a series of needles 6 and reciprocated horizontally by means of the usual well-known mechanism not shown, while at the rear of the fabric (see Fig. 2) shuttles 7 are operated in the well known manner by means of the usual shuttle operating mechanism 8 supported on the machine frame. Each of the needles 6 is supplied with a thread 9 which is tensioned and fed in any conventional manner.

In the preferred embodiment of this invention, each needle has associated therewith a guiding element 10 for the ornamental material 11 to be sewed by such needle to the fabric and said guiding element is, in accordance with our invention, caused to move about the needle as an axis in a simple arcuate path, so that such ornamental material may be accurately guided in advance of the needle to faithfully follow any design throughout any angle or angles thereof. In the preferred embodiment of our invention illustrated, the ornamental material 11 is passed beneath a guide ring 12 on the needle bar and is fed from elevated spools 13 suitably mounted on rods or shafts 14. The movement of the guiding element 10 in an arcuate path about the needle is preferably effected by providing for each needle a guiding element or ring 10 in a member rotatable about the needle as an axis, and in the preferred embodiment shown, a guide wheel 15 has an aperture 16 surrounding its axis through which the needle is adapted to reciprocate, said guide 10 being disposed in a

radial direction from the position of the needle in said axial aperture 16 so that a turning of the wheel 15 will cause a movement of the radially or eccentrically disposed guide 10 to be moved in an arcuate path about the said needle 6.

Means for rotating said guide wheels about the needles for the purpose of following the design is provided, and in the preferred form shown this is accomplished by a worm gear, the said guide wheel 15 being a worm-wheel having worm-teeth 17 on its periphery meshing with a worm 18 mounted on a shaft 19 suitably supported in the frame of the machine. As illustrated, two parallel shafts 19 are employed to operate two series of guide wheels and each shaft is continuous across the machine and passes through bearing apertures 20^b in mounting brackets 20 between the side members 20^a of which brackets the worm 18 is arranged. As shown, each of the mounting brackets is supported on a continuous rod 21 which in turn is mounted upon a supporting bar 22 suitably connected at the opposite ends of the machine. It will be obvious that a rotation of the worm 18 by the shaft 19 will cause the guiding elements 10 to be moved in an arcuate path about the needle 6 which passes through the aperture 16 of the wheel 15, and that in view of this arcuate movement about the needle as a center the material 11 may be moved to register accurately and faithfully along the path of any design which the movement of the fabric may cause the needle to follow.

In the preferred embodiment of our invention shown the shafts 19 are preferably rotated by power for the purpose of moving the guiding elements 10 in an arcuate path as distinguished from a hand movement thereof, and as illustrated these shafts are rotated by means of a motor 23 which is geared to such shafts 19. The two shafts 19 are, as shown, provided at their ends with spiral gears 25 which mesh with spiral gears 24 on a vertical shaft 26, which at its lower end is provided with a spiral gear 27 which meshes with a spiral gear 28 on the shaft 29 of the motor 23. To give the shafts 19 rotary motion in opposite directions about the needle so as to permit the circular or arcuate guiding movement in opposite directions about the centrally disposed needle, we provide means for turning the shaft 29 of the motor 23 in opposite directions. This may be accomplished in any well known manner and, as illustrated, we provide button switches 30—31 suitably connected by means of a flexible wire connection 32 extending from binding posts 23^a on the motor to an extension 4^a on the hand-operated pantograph 4.

The turning movement of the elements 10 and its position in relation to the needle is also preferably indicated on the hand-op-

erated pantograph 4 by means of a pointer 33. This indicator pointer 33 is operated to move synchronously with the guiding element by suitable connections with the shafts 19, so that rotary movement of the said shafts to cause the guiding element to be swung about its center will likewise cause the pointer 33 to be swung in the same direction about its pivot 34 which comprises the 10 needle indicator. The guiding pointer will thus faithfully indicate the position in relation to the needle of the said guiding element. As illustrated, the means for moving the pointer 33 comprises the extension 15 upwardly of the upright transmission shaft 26 and the provision on the upper end of this shaft of a bevelled pinion 35 which, as shown, meshes with bevelled gear teeth 36 on a sprocket wheel 37 which is connected 20 by a sprocket chain 38 to a similar sprocket having bevelled gear teeth 40 meshing with a bevelled pinion 41 on the end of a rod 42, which also has a bevelled pinion 43 at its opposite end and transmits motion to a bevelled gear wheel 44 on the pantograph frame, which meshes with a pinion 45 on the 25 end of a vertical rod 46 having at its opposite end a bevelled pinion 47, which meshes with a bevelled wheel 48 having its axis 30 registering with the needle indicator or pointer 33 of the pantograph. As illustrated, (see Figs. 1 and 3) said bevelled wheel 48 is provided with an inward extension 34^a having the pointed end 34 at the axis of the 35 said wheel 48 and the guide indicating pointer 33 projects radially therefrom, it being understood of course that the guide indicating pointer is arranged initially to project radially from the needle indicating pointer in a direction similar to the direction in which the guiding element 10 is positioned in relation to the needle, and that any turning movement of the transmission shaft for the guiding element will turn the 40 pointer and the guide through equal degrees of an arc.

The mechanism hereinabove described may, is desired, be utilized, without further additions, to sew ornamental material on the fabric but in such case it will be necessary to use the usual zig-zag stitching, which stitching in either hand stitching or automatic stitching may be made to traverse obliquely the line of travel of the guide which, as aforesaid, will be moved to faithfully register with the line of the design.

In order to sew the goods to the fabric with a straight stitching which follows the line of the design and which is much more desirable because it saves labor, thread and simulates hand stitching more effectively, we provide means for oscillating the guides about the needle to opposite sides of the position of such guides when the same register with or overlie the line of the design. We

preferably provide a movement independent of the rotary movement above described for accomplishing this purpose, and as illustrated we provide means for reciprocating the transverse shafts 19 on which the worms 18 are fixedly mounted, it being understood that such reciprocation of the shafts and worms will, because of the meshing of the worm with the worm wheels 15, oscillate the said worm wheels 15 about the needle, thus oscillating the guiding elements 10 across and to opposite sides of the position which such guides would otherwise normally occupy and which design-following or registering position is indicated by the pointer 33. 80

In the preferred form illustrated, we provide each of the shafts 19 with thrust bearings 50 and link the shafts together by means of a link rod 51, each of the thrust bearings 50 being retained in place on the shaft by 85 collars 50^a having anti-friction device, as shown, interposed between such collars and the thrust bearings. Said shafts may thus be reciprocated synchronously with the movement of the needles so as to swing the ornamental material to opposite sides thereof as each stitch is made. As shown, we have for this purpose connected to the link 51 a connecting rod 52 which is pivoted eccentrically on the intermittent gear wheel 53, 90 which rides upon an intermittent gear wheel 54 which is driven by a sprocket wheel 55 on a shaft 55^a, connected by a sprocket chain 56 to another sprocket wheel 57 on a rotating shaft of the machine. 100

In order to permit the shafts 19 to be reciprocated and at the same time to be turned, we have connected the ends of these shafts by a pin and slot connection 58 with a rotatable sleeve shaft 59, on which last-mentioned shaft the rotating spiral 25 is mounted for the purpose of turning. It will be obvious from this arrangement that the sleeve shaft may be rotated to transmit rotation to the transmission shafts 19 and at 110 the same time the shafts 19 may be reciprocated longitudinally within the sleeve shafts owing to the slot and pin connection therewith.

The aforesaid independent reciprocating motion which, as above stated, is translated into an oscillating motion of the guiding elements 10 causes the said guiding elements to be oscillated to opposite sides of the needle and causes the material to be moved in a substantially zig-zag path across a line of straight stitches which follow the design. Because movement of the guiding elements 10 is oscillating and arcuate the material may be swung to proper angles with such stitches at opposite sides of the line of the design by a relative short movement and the same angle is formed with the stitching at all points of the design. 125

The guide wheel 15, as above specified, is 130

4
supported in a bracket 20 and in the preferred embodiment shown the side walls 20^a—20^b of the bracket form stops which contact with the bosses 18^a of the worm 18 to 5 limit the longitudinal reciprocating movement of such worms and their shaft 19. Said bracket 20, furthermore, is provided at its upper end with a ring frame 20^c (see Fig. 6) within which the guide wheel 15 is mounted 10 and on the inner circumference of which the outer periphery of said guide wheel is adapted to bear. The wheel in the embodiment shown is made in two split parts and is locked within the frame by a locking ring 15 15 20^d connected to the wheel body 15 and locked within the frame 20^c by means of the screws 20^e.

Having described our invention, we claim:—

20 1. In an embroidery machine having stitching mechanism including horizontally-reciprocated needles, guiding elements for ornamental material to be sewed by the needles to the fabric, power-actuated means for 25 moving the said guiding elements in arcuate paths about the needles in the plane of the fabric to enable the registration of such guiding elements with the design, and means for manually controlling the extent 30 and direction of said power-actuated movement.

2. In an embroidery machine having stitching mechanism including horizontally-reciprocated needles and a hand-operated 35 pantograph, guiding elements for ornamental material to be sewed by the needles to the fabric, power-actuated means for moving the said guiding elements in arcuate paths about the needles in the plane of the fabric to enable the registration of such guiding elements with the design, means on the hand-operated pantograph for indicating the radial position of such guides in relation to the needles, and means on the hand-operated 40 pantograph for operating the said power means, to control the extent and direction of said power-actuated movement.

3. In an embroidery machine having stitching mechanism including horizontally-reciprocated needles and a hand-operated 45 pantograph, guiding elements for ornamental material to be sewed by the needles to the fabric, an electric motor for moving the said guiding elements in arcuate paths about the needles in the plane of the fabric to enable the registration of such guiding elements with the design, means on the hand-operated pantograph for indicating the radial position of such guides in relation to the needles, and a switch on the pantograph 50 for controlling the said electric motor.

4. In an embroidery machine having stitching mechanism including horizontally-reciprocated needles, guiding elements for 55 ornamental material to be sewed by the nee-

dles to the fabric, power-actuated means for moving the said guiding elements in arcuate paths about the needles in the plane of the fabric to enable the registration of such guiding elements with the design, means for 70 manually controlling the extent and direction of said power-actuated movement, and means for causing an oscillating movement of the said guiding elements about the needles at the varying points of registration with the design in said first-mentioned arcuate line of movement.

5. In an embroidery machine having stitching mechanism including horizontally-reciprocated needles and a hand-operated 80 pantograph, guiding elements for ornamental material to be sewed by the needles to the fabric, an electric motor for moving the said guiding elements in arcuate paths about the needles in the plane of the fabric to enable the registration of such guiding elements with the design, means on the hand-operated pantograph for indicating the radial position of such guides in relation to the needles and a pair of switches on the 85 pantograph for causing the shaft of said motor to be rotated in opposite directions.

6. In an embroidery machine having stitching mechanism including horizontally-reciprocated needles, guiding elements for ornamental material to be sewed by the needles to the fabric, power-actuated means for moving the said guiding elements in arcuate paths about the needles in the plane of the fabric to enable the registration of such guiding elements with the design, means for 90 manually-controlling the extent and direction of said power-actuated movement, and independent means for oscillating said guiding elements about the needles at the varying points of registration with the design in said first-mentioned arcuate line of movement.

7. In an embroidery machine having stitching mechanism including horizontally-reciprocated needles, bearing-rings surrounding said needles, guide-wheels mounted in vertical position with one of its sides disposed closely adjacent to the fabric and having their axes registering with the said horizontally reciprocating needles and having peripheral bearing on said bearing rings, means for supporting said bearing rings, guiding elements on said rings positioned radially from said axes, worm gears for rotating said guide-wheels to move the guiding elements in arcuate paths about the needles in the plane of the fabric to enable registration of such guiding elements with the design and means for operating said worm 100 gears.

8. In an embroidery machine having stitching mechanism including horizontally-reciprocated needles, a series of bearing 105 rings surrounding said needles, guide wheels 110

having their axes registering with the said horizontally reciprocating needles and having a peripheral bearing on said bearing rings, means for supporting said bearing rings, guiding elements on said rings positioned radially from said axes, a continuous horizontal shaft; a series of worms mounted on said shaft; said guide wheels having worm teeth meshing with said worms and means for rotating said continuous shaft to rotate the guide wheels and to move the guiding elements in arcuate paths about the needles in the plane of the fabric to enable registration of such guiding elements with the design.

9. In an embroidery machine having stitching mechanism including horizontally-reciprocated needles, a series of bearing rings surrounding said needles, guide wheels having their axes registering with the said horizontally-reciprocating needles and having a peripheral bearing on said bearing rings, means for supporting said bearing rings, guiding elements on said rings positioned radially from said axes, a continuous horizontal shaft; a series of worms mounted on said shaft; said guide wheels having worm teeth meshing with said worms, power-actuated means for rotating said continuous shaft to rotate the guide wheels and to move the guiding elements in arcuate paths about the needles in the plane of the fabric to enable registration of such guiding elements with the design, means for manually controlling the extent and direction of said power-actuated movement, and means for reciprocating said shaft to oscillate said guide at varying points in its rotary design-registering movement.

10. In an embroidery machine having stitching mechanism including two lines of horizontally-reciprocated needles, two lines of bearing rings surrounding said needles; two series of guide wheels having their axes registering with the said horizontally-reciprocating needles and having a peripheral bearing on said bearing rings, means for supporting said bearing rings, guiding elements on each of said wheels positioned radially from said axes, a pair of continuous horizontal parallel shafts; a series of worms on each shaft; worm teeth on said guide wheels meshing with said worms, power-actuated means for synchronously rotating both shafts to move the guiding elements on each series of guide wheels in arcuate paths about the needles in the plane of the fabric to enable registration of such guiding elements with the design, and means for manually controlling the extent and direction of said power-actuated movement.

11. In an embroidery machine having stitching mechanism including two lines of horizontally-reciprocated needles, two lines

of bearing rings surrounding said needles; two series of guide wheels having their axes registering with the said horizontally-reciprocating needles and having a peripheral bearing on said bearing rings, means for supporting said bearing rings, guiding elements on each of said wheels positioned radially from said axes, a pair of continuous horizontal parallel shafts; a series of worms on each shaft; worm teeth on said guide wheels meshing with said worms, power-actuated means for synchronously rotating both shafts to move the guiding elements on each series of guide wheels in arcuate paths about the needles in the plane of the fabric to enable registration of such guiding elements with the design, means for manually controlling the extent and direction of said power-actuated movement, and means for reciprocating said shafts to oscillate said guide at varying points in its rotary design-registering movement.

12. In an embroidery machine having stitching mechanism including horizontally-reciprocated needles, guiding wheels having their axes registering with the horizontally reciprocating needles and having integrally formed worm teeth, a continuous shaft having worms meshing with the worm teeth, of said wheels, guiding elements for ornamental material positioned radially from the axes of such wheels, and means for rotating said shaft.

13. In an embroidery machine having stitching mechanism including horizontally reciprocated needles, guiding wheels having worm teeth and having their axes registering with the horizontally reciprocating needles, guiding elements for ornamental material positioned radially from the axes of such wheels, a rotatable horizontally-disposed operating shaft for rotating said wheels, means for rotating said shaft; and means for reciprocating said horizontally-disposed shaft to oscillate the guide wheel independently of its first mentioned rotary movement.

14. In an embroidery machine having stitching mechanism including horizontally reciprocated needles, guiding wheels having their axes registering with the horizontally reciprocating needles and having integrally formed worm teeth, guiding elements for ornamental material positioned radially from the axes of such wheels, a horizontally-disposed shaft having worms meshing with the worm teeth of said wheel, power-actuated means for rotating said shaft, means for manually controlling the extent and direction of said power-actuated movement, and means for reciprocating said shafts to oscillate the guide wheel independently of its first-mentioned rotary movement.

15. In an embroidery machine having stitching mechanism including horizontally-

reciprocated needles, guiding wheels having their axes registering with the horizontally reciprocating needles and having integrally formed worm teeth, guiding elements for ornamental material positioned radially from the axes of such wheels, two parallel horizontal shafts having worms meshing with the worm teeth of said wheels, power-actuated means for rotating said shafts to 10 rotate said guide wheels and enable registration of the guiding elements with the de-

sign, means for manually controlling the extent and direction of said power-actuated movement, and means for synchronously reciprocating both shafts to oscillate the guiding elements at the varying design-registering positions reached by said rotary movement. 15

In witness whereof, we have signed our names to the foregoing specification.

JACOB HOHL.

ERNEST G. KELLER.
